HOT WATER STOVE AND STORAGE TANK

Filed Sept. 10, 1930

UNITED STATES PATENT OFFICE

ELBERT A. CORBIN, JR., OF SWARTHMORE, PENNSYLVANIA

HOT WATER STOVE AND STORAGE TANK

Application filed September 10, 1930. Serial No. 480,906.

The object of this invention is to devise a combined hot water heater and storage tank wherein the tank is an integral part of the hot water heater and has sufficient storage capacity to provide a constant hot water supply for the average household.

With the above and other objects in view as will hereinafter clearly appear, my invention comprehends a novel combined hot water heater and storage tank.

Other novel features of construction and advantage will hereinafter more clearly appear in the detailed description and the appended claims.

15 For the purpose of illustrating the invention, I have shown in the accompanying drawings preferred embodiments of it, which, in practice, will give satisfactory and reliable results. It is, however, to be understood that these embodiments are typical only, and the various instrumentalities of which my invention consists can be variously arranged and organized, and the invention is not limited to the exact arrangement and organization of these instrumentalities as herein set forth.

Figure 1 is a front elevation of a combined hot water stove and storage tank, embodying my invention.

30 Figure 2 is a section on line 2—2 of Figure 1.

Figure 3 is a section on a reduced scale on line 3—3 of Figure 2.

Similar numerals of reference indicate corresponding parts.

Referring to the drawings:—

1 designates a hot water heater of the domestic type with which is combined a storage tank 2, which is preferably in vertical alignment therewith.

45 The hot water heater 1 is provided with an outer casing 3, which is insulated as at 4, the insulation being outwardly of the outer water jacket wall 5, which with the inner water jacket wall 6, forms the water jacket chamber 7. 8 and 9 designate downwardly inclined baffles, the baffle 9 being longer than the baffle 8, and these two baffles are hollow and in free communication with the water jacket chamber 7 and form water legs extending com-

pletely across the cylinder formed by the inner water jacket wall 6.

The juxtaposed side walls of the baffles 8 and 9 extend to and are connected with the outer water jacket wall 5. The baffle 8 forms the roof of the combustion chamber 10 and contributes with the baffle 9 to form the exit flue 11 which leads from the combustion chamber 10 to the smoke box 12.

55 The top wall of the baffle 9 partially supports the fuel in the fuel magazine 13, which is provided with a door 14. The fuel passes from the fuel magazine through the throat 15 to the fuel bed 16 which is supported by an inclined grate 17 having an operating 60 handle 18.

65 The shaking movement of the grate is in a rectilinear direction and delivers the ash to a pan 19 in the ash pit 20 having a door 21. 22 is a controllable drain from the water 70 jacket chamber 7. The upper end of the hot water stove is closed by the bottom wall 23 forming the bottom header of the storage tank. This bottom wall is sealed with the upper ends of the water jacket walls 5 and 6 75 and seals and closes the top of the fuel magazine.

75 The bottom wall 23 is sealed with the cylinder 24 which is sealed with the top header 25. The cylinder 24 is surrounded by insulation 26 which also extends over the top header, and an outer casing 27 is provided.

80 The cold water inlet pipe 28 passes through the top header and terminates a desired distance above the bottom header 23. The hot water exit 29 from the hot water magazine 30 leads to a desired point of utilization.

85 Ports 31, see Figure 3, permit the hot water to pass by gravity from the hot water magazine 30 to the chamber 7. The hot water passes from the chamber 7 through slots 32 into a funnel-shaped fitting 33 which discharges into the pipe 34 which terminates a desired distance from the top header 25.

90 35 designates an automatic damper control of any desired or conventional type which communicates at 36 with the hot water magazine and is controlled by the temperature of the hot water. This damper control 35, is connected by a cable 37 and conventional link- 95 100

age with a damper 38 for the smoke box 12 and by a cable 39 and conventional linkage with a damper 40 controlling introduction of atmospheric air to the ash pit for primary combustion.

5 The operation will now be clear to those skilled in this art and is as follows:—

In order to start the heater, the kindlings are introduced through the door controlled

16 opening 41. The cold water enters from the source of cold water supply through the pipe 28. The cold water in the hot water magazine passes through the ports 31 into the water jacket chamber 7 creating an unbalanced condition in the hot water magazine 30. The hot water passes from the baffles 8 and 9 into the slots 32 in the bottom header into the fitting 33 and therefrom to the pipe 34. The hot water is withdrawn through the pipe 29. As the temperature of the water increases to a desired standard, the automatic control 35 causes the damper 38 to open and the damper 40 to close.

25 In my present invention, I combine a unitary structure, a gravity fed fuel magazine heater and a hot water storage tank with an automatic damper control of the source of heat. This enables one to operate the device for a period of at least twenty-four hours 30 without any attention on the part of the operator. At the end of such period, the grate should be shaken and the coal magazine filled.

35 My combined hot water heater and storage tank can be manufactured at a much less cost than where a separate tank is used; and the cost of installation is also materially reduced.

40 Special attention is directed to the novel construction and arrangement of water legs 45 communicating in a novel manner with the bottom header of the storage tank. The hot water passes directly from the water jacket into the storage tank with no losses due to radiation or other causes as is the case where the heater and tank are separated and connected by outside pipes and fittings.

Having thus described my invention what I claim as new and desire to secure by Letters Patent, is:—

50 1. A domestic hot water heater having in combination a water jacketed coal heater and a storage tank, arranged one above the other and forming a unit of structure, said heater jacket having at its upper end downwardly inclined water legs in direct communication with said jacket and forming the exit for the products of combustion, and a connection from one of said legs leading through the bottom of the storage tank and discharging near the top of the latter.

55 2. A domestic hot water heater having in combination a water jacketed heater and a storage tank, arranged one above the other and forming a unit of structure, said heater jacket having at its upper end downwardly

inclined water legs in direct communication with said water jacket and forming the exit for the products of combustion, one of said legs having a communication discharging into said storage tank near its upper end, 70 said heater having a coal magazine which is closed by the bottom of said storage tank, and one wall of said magazine is formed by one of said water legs.

3. A domestic hot water heater having in combination a water jacketed heater and a storage tank, arranged one above the other and forming a unit of structure, said heater jacket having downwardly inclined water legs forming between them a restricted 75 throat for the products of combustion, one of said legs being in direct communication with said water jacket and one of said legs discharging into said tank near its upper end; the bottom of said tank being provided 80 with circumferentially spaced ports communicating with the jacket of said heater.
